(57) **CLAIM**

The ornamental design for a golf hitting mat as shown and described.

DESCRIPTION

FIG. 1 is a perspective view of a golf hitting mat showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a second embodiment of the golf hitting mat, where the rear, left, right, top and bottom views are identical to the design shown in FIGS. 4-8; and,

FIG. 10 shows the design of FIG. 9, in an alternate configuration.

The broken lines shown in FIGS. 9-10 show portions of the golf hitting mat that form no part of the claimed design.

1 Claim, 10 Drawing Sheets
